189,496

WASHBOARD OR THE LIKE

Jessie Pearl Kinyon, 201 W. 79th St., New York, N.Y.

Filed Feb. 29, 1960, Ser. No. 59,564

Term of patent 14 years

(Cl. D49—1)

FIG. 1

FIG. 2

Figure 1 is a plan elevational view of a washboard or the like showing my design; and

Figure 2 is a side elevational view thereof.

The back of the washboard is plain and unornamented.

I claim:

The ornamental design for a washboard or the like, as shown and described.

References Cited in the file of this patent

UNITED STATES PATENTS

D. 122,834	Bloom	Oct. 1, 1940
2,271,512	Griffiths	Feb. 3, 1942